UNITED STATES PATENT OFFICE

FREDERICK W. SULLIVAN, JR., AND CHESTER E. ADAMS, OF HAMMOND, INDIANA,
ASSIGNORS TO STANDARD OIL COMPANY, OF CHICAGO, ILLINOIS, A CORPORATION
OF INDIANA

ANTISOLVENT DEWAXING OF OIL

No Drawing.

Application filed June 24, 1930. Serial No. 463,567.

This invention relates to the removal of wax from oils and particularly from petroleum lubricating oils.

The object of the invention is to provide a more efficient and a more economical means for removing wax from petroleum lubricating oils. A further object is to facilitate the preparation of oils having lower cold tests than have heretofore been obtainable. A further object is to provide a dewaxing system wherein the wax may be removed by filtration at rapid rates. Other objects will be apparent as the description of the invention proceeds.

The invention does not extend to the broad idea of diluting an oil with naphtha, methyl-ethyl ketone, butyl alcohol, acetone, benzene, etc., chilling and mechanically separating out the solidified wax. We have discovered that the monocarbon organic acid esters of simple alcohols, such as methyl or ethyl formates or carbonates, are particularly and unexpectedly effective as antisolvents in removing wax from oils. We have discovered that by the process hereinafter set forth we can obtain at a given chill temperature lower cold tests than can be obtained by the use of diluents heretofore used, and at the same time we can obtain satisfactory filter cakes and high filter rates.

Our invention may be applied to any wax bearing oil, but by way of illustration we will describe its application to a treated and percolated overhead lubricating oil (from mid-continent crude) having a viscosity of about 75 seconds Saybolt at 210° F. Such an oil contains a large amount of wax which is difficult to remove either by filtration, settling or centrifuging.

Our antisolvent is an ester of a monocarbon organic acid, such as methyl formate, ethyl formate, methyl carbonate, ethyl carbonate, etc. For reasons which we are unable to explain it appears that compounds of this particular character or class offer several new and unexpected advantages. They bring about a more complete removal of wax and thereby make it possible to obtain an oil of lower cold test than has been obtained with diluents heretofore used. They also cause a

separation of the wax in a physical form which expedites filtration.

Our antisolvents, the esters of monocarbon organic acids, are not miscible in all proportions with oil and it is therefore advisable to use an agent for promoting miscibility. We prefer to use benzene (benzol) for this purpose but other miscibility agents, such as toluol, may be used.

The relative proportion of antisolvent to miscibility agent in our diluent is dependent on the particular substances used, on the temperatures at which the oil is filtered, and on the ratio of diluent to oil. The number of parts by volume of antisolvent which should be present in 100 parts of diluent (antisolvent plus benzene) is set forth in the following table:

Optimum amounts of antisolvent

Antisolvent	1 oil:2½ dil. -10° F.	1 oil:1 dil. -20° F.	1 oil:4 dil. -20° F.	70
Methyl formate.....	33	32	37*	
Ethyl formate.....	54	35-40	45	
Methyl carbonate.....	37	32-36	37*	
Ethyl carbonate.....	72	36-70	38-70	75

* At -10° F.

In dewaxing petroleum lubricating oils we prefer to dilute the oil with two and one-half times its volume of diluent (antisolvent-benzene mixture). The ratio of diluent to oil may be from 1:1 to 4:1, but the lower ratios give low filtration rates and the higher ratios increase dewaxing costs due to solvent losses. A ratio of 1:2½ gives the best results, particularly when it is desired to automatically discharge the wax cake from a filter press.

The mixture of diluent and oil is rapidly chilled to a temperature of about -10° F. with or without slight agitation. A small amount of porous cellular silica (diatomaceous earth or infusorial earth), preferably about two-thirds of a pound per gallon of oil, is added to the chilled mixture to prevent any wax particles from getting through the filter cloth and to increase the rate of filtration. The mixture is then filtered through a conventional press, preferably one

having cloth covered plates or leaves. The filtration may be carried out under a partial vacuum and means may be employed to circulate solvent vapors through a closed system 5 to prevent loss thereof. These features per se form no part of this invention and they will therefore not be described.

While our invention has been described in a process for separating wax from oil by 10 filtration, it is understood that we do not limit ourselves to the details above set forth except as defined by the following claims:

We claim:

1. The method of separating viscous oil 15 from wax which comprises diluting it with about two and one-half times its volume of a substantially optimum mixture of a miscibility agent and an ester of a monocarbon organic acid, chilling the diluted oil and mechanically separating the wax from the chilled oil.
2. The method of claim 1 wherein porous cellular silica is added to the cold oil prior to filtration.
3. In a method of separating oil from wax, 25 the step which comprises diluting an oil-wax mixture with a diluent containing an ester of a monocarbon organic acid.
4. In a method of separating oil from wax, 30 the step which comprises diluting an oil-wax

mixture with a diluent containing an ester of formic acid.

5. In a method of separating oil from wax, the step which comprises diluting an oil-wax mixture with a diluent containing an ester 75 of carbonic acid.

6. In a method of separating oil from wax, the step which comprises diluting an oil-wax mixture with a diluent containing about 36-72% ethyl carbonate and 64-28% benzene. 75

7. In a method of removing a paraffin material from oil, the step which comprises diluting said oil with a formate of a lower alcohol of the fatty series and an organic solvent. 80

8. In a method of removing a paraffin material from oil, the step which comprises diluting it with a mixture of a formate of a lower alcohol of the fatty series and an organic solvent, and mechanically separating the paraffin material from the diluted mixture. 85

9. The process of claim 7 in which the organic solvent is benzene.

10. The process of claim 8 wherein the organic solvent is benzene. 90

Signed this 16th day of June, 1930, at Whiting, in the county of Lake, State of Indiana.
